BUOYANT ELECTRIC CABLE

Harry L. Beede, Fort Lee, N. J., assignor to The Okonite-Callender Cable Company, Incorporated, Paterson, N. J., a corporation of New Jersey

Original application February 6, 1943, Serial No. 474,932. Divided and this application January 6, 1944, Serial No. 517,166

12 Claims. (Cl. 174—110)

This invention relates to an improvement in buoyant electric cables, namely, that type of electric cable wherein the weight to volume ratio is such as to enable the same to float in a medium such as sea water.

One of the objects of my invention is to provide a cable of this type which is long lived in service, and one which is not readily crushed by externally applied pressure.

In the drawing accompanying this application:

Fig. 1 is a fragmentary sectional elevational view of one embodiment of the invention; and

Fig. 2 is a similar view of another embodiment.

Referring to the drawing in detail: 2 designates cylinders of plywood, hermetically sealed with plywood heads 4. For purposes of description these sealed cylinders will be referred to hereinafter as cells or core cells.

Each of the core cells is enclosed in a suitable water and moisture resistant plastic film, covering or sheath 6. Many types of plastic may be employed. I have obtained good results employing a phenolic condensation product such as Bakelite.

The core cells are laid end to end along the cable, adjacent cells being separated by spacers 8. These spacers are preferably of resilient material such as rubber, the spacers illustrated being cellular rubber each enclosed in a rubber skin 10.

The cable conductor is designated 12. This conductor may be applied directly about the cell-and-spacer assembly, but I prefer first of all to enclose the cell-and-spacer assembly in a water-impervious flexible, rubber-like sheath 14, and to apply the conductor 12 about this sheath.

On the exterior of the cable I apply a rubber or other water-impervious sheath 16.

The core cells are highly resistant to crushing if constructed as described. However, it is within the contemplation of my invention to maintain these cells under internal pressure, say seventy-five to one hundred pounds per square inch.

When employing the rubber-like sheath 14 immediately over the cell-spacer assembly I find that in the vulcanizing operation the sheath becomes bonded to the spacers. This is advantageous in that it provides a seal at the periphery of each spacer against the passage of water along the interior of the cable.

A buoyant cable such as above described is not only highly resistant to crushing, but will not corrode readily and is highly resistant to water and moisture absorption.

In the embodiment of my invention and illus-

trated in Fig. 2, I show a construction similar to that just described, except that in this instance both the cylinders 2 and heads 4 are shown as of plywood construction, each being made up of alternate plies of wood and a water and moisture resisting plastic such as Bakelite. In all other respects the construction in Fig. 2 is a duplicate of that of Fig. 1.

This application is a division of my copending application Serial No. 474,932, filed February 6, 1943.

What I claim is:

1. In a buoyant electric cable in which the weight to volume ratio is such as to enable the same to float in sea water, the combination of a plurality of center or core cells each comprising a hermetically sealed plywood cylinder enclosed in a water and moisture resistant plastic, spacers intermediate adjacent cells, a conductor disposed about the cell-and-spacer assembly, and an outer, flexible, water-impervious enclosing sheath.

2. In a buoyant electric cable in which the weight to volume ratio is such as to enable the same to float in sea water, the combination of a plurality of center or core cells each comprising a hermetically sealed plywood cylinder enclosed in a phenolic condensation product, resilient spacers intermediate adjacent cells, a conductor disposed about the cell-and-spacer assembly, and an outer, flexible, water-impervious enclosing sheath.

3. In a buoyant electric cable in which the weight to volume ratio is such as to enable the same to float in sea water, the combination of a plurality of center or core cells each comprising a hermetically sealed plywood cylinder enclosed in a water and moisture resistant plastic, spacers intermediate adjacent cells, a rubber-like, water-impervious sheath about said cell-and-spacer assembly, a conductor about said sheath, and an outer, flexible, water-impervious enclosing sheath.

4. In a buoyant electric cable in which the weight to volume ratio is such as to enable the same to float in sea water, the combination of a plurality of center or core cells each comprising a hermetically sealed plywood cylinder enclosed in a phenolic condensation product, spacers intermediate adjacent cells, a rubber-like, water-impervious sheath about said cell-and-spacer assembly, a conductor about said sheath, and an outer, flexible, water-impervious enclosing sheath.

5. In a buoyant electric cable in which the weight to volume ratio is such as to enable the same to float in sea water, the combination of a

plurality of center or core cells, each under internal superatmospheric pressure and comprising a hermetically sealed plywood cylinder enclosed in a water and moisture resistant plastic, spacers intermediate adjacent cells, a conductor disposed about the cell-and-spacer assembly, and an outer, flexible, water-impervious enclosing sheath.

6. In a buoyant electric cable in which the weight to volume ratio is such as to enable the same to float in sea water, the combination of a plurality of center or core cells, each under internal superatmospheric pressure and comprising a hermetically sealed plywood cylinder enclosed in a phenolic condensation product, spacers intermediate adjacent cells, a conductor disposed about the cell-and-spacer assembly, and an outer, flexible, water-impervious enclosing sheath.

7. In a buoyant electric cable in which the weight to volume ratio is such as to enable the same to float in sea water, the combination of a plurality of center or core cells, each under internal superatmospheric pressure and comprising a hermetically sealed plywood cylinder enclosed in a water and moisture resistant plastic, spacers intermediate adjacent cells, a rubber-like sheath about the cell-and-spacer assembly, a conductor disposed about said sheath, and an outer, flexible, water-impervious enclosing sheath.

8. In a buoyant electric cable in which the weight to volume ratio is such as to enable the same to float in sea water, the combination of a plurality of center or core cells, each under internal superatmospheric pressure and comprising a hermetically sealed plywood cylinder enclosed in a phenolic condensation product, spacers intermediate adjacent cells, a rubber-like water-impervious sheath about said cell-and-spacer assembly, a conductor disposed about said sheath, and an outer, flexible, water-impervious enclosing sheath.

9. In a buoyant electric cable in which the weight to volume ratio is such as to enable the same to float in sea water, the combination of a plurality of center or core cells each comprising a plywood cylinder composed of alternate plies of wood and a water and moisture resistant

plastic, plywood heads for the cylinders hermetically sealed in place, water and moisture resistant plastic enclosing each cylinder, resilient spacers intermediate adjacent cells, a conductor about 5 the cell-and-spacer assembly, and an outer, flexible, water-impervious enclosing sheath.

10. In a buoyant electric cable in which the weight to volume ratio is such as to enable the same to float in sea water, the combination of a plurality of center or core cells each comprising a plywood cylinder composed of alternate plies of wood and a water and moisture resistant plastic, heads for the cylinders of the same material as the cylinders and hermetically sealed in place, water and moisture resistant plastic enclosing each cylinder, resilient spacers intermediate adjacent cells, a conductor about the cell-and-spacer assembly, and an outer, flexible, water-impervious enclosing sheath.

11. In a buoyant electric cable in which the weight to volume ratio is such as to enable the same to float in sea water, the combination of a plurality of center or core cells each comprising a plywood cylinder composed of alternate plies of wood and a water and moisture resistant plastic, plywood heads for the cylinders hermetically sealed in place, water and moisture resistant plastic enclosing each cylinder, resilient spacers intermediate adjacent cells, a rubber-like 25 water-impervious sheath about the cell-and-spacer assembly, a conductor about said sheath, and an outer, flexible, water-impervious enclosing sheath.

12. In a buoyant electric cable in which the weight to volume ratio is such as to enable the same to float in sea water, the combination of a plurality of center or core cells each comprising a plywood cylinder composed of alternate plies of wood and a phenolic condensation product, 35 heads for the cylinders hermetically sealed in place and composed of the same material as the cylinders, each cell being enclosed in a phenolic condensation product, a rubber-like sheath about the cell-and-spacer assembly, a conductor about said sheath, and an outer, flexible, water-impervious enclosing sheath.
